COMBINED SPINNING WHEEL AND ANIMATED

Robert H. Jarpey, 1286 W. 29th St., Los Angeles, Calif.

Filed Feb. 28, 1964, Ser. No. 78,825

Term of patent 3½ years

(Cl. D34—15)

Fig. 1

The side of the base portion not shown is substantially similar to that shown.

I claim:

The ornamental design for a combined spinning wheel and animated figure toy or similar article, substantially as shown and described.
